10

This invention relates to a method for making embossed decorative articles and more particularly to a method for making resilient decorative articles having embossed elevated and depressed decorative portions by means of dielectric heating.

Dielectric heating is a selective heating process whereby heat can be developed within an electrical insulating or dielectric material. Since a dielectric material is one which does not normally conduct any appreciable amount of electrical current, dielectric heating does not result from the resistance of the material to current flow but rather from the frictional heating caused by the forced back and forth rotating movement of the molecules of the material. The force that produces the heating will be uniform throughout the material if the material has a uniform molecular arrangement and if the electrical field strength is uniform.

When the dielectric material is placed in an electrical field such as exists between two plates or electrodes having a voltage impressed across them, whereby one of the planes is positive and the other is negative, the molecules of the dielectric material appear to stretch out and elongate themselves so that one end of the molecule has a positive charge which points toward the electrode with a negative charge and the other end of the molecule has a negative charge which points toward the electrode with the positive charge.

If the charge between the plates is reversed so that the positive plate now becomes negative and vice versa, the molecules will rotate to realign themselves. Thus, if an alternating current of radio frequency is impressed across the electrodes, the electrodes will continually change their charge and the molecules of the dielectric material will be forced to rotate back and forth as the electrodes change their charge. As the molecules of the dielectric material rotate back and forth, heat will be developed within the dielectric material, although the electrodes will not become heated except by conduction from the heated dielectric material if they are in contact therewith.

Various methods of making decorative articles or trim assemblies having elevated and depressed portions are known and it is also known to make such articles by means of dielectric heating. However, in such methods only the depressed portions of the articles are embossed while the elevated portions thereof are not embossed in any manner since they are formed merely as the result of embossing various depressed areas or portions of the articles. The method of this invention differs from such prior methods in that both the elevated and depressed areas of the articles are embossed so that the finished article includes an integral well defined decoration. While the method may be used to make various articles, it is preferably used to make resilient articles which comprise an outer layer of heat fusible material provided with a backing layer of heat fusible compressible material. The outer layer and backing layer are secured together

2

along a continuous depressed and embossed area and are also secured together by an elevated embossed area within and bounded by the continuous depressed area. The backing layer is compressed within both the depressed and elevated area and the method utilizes dielectric heating.

The primary object of this invention is to provide a new and improved method for making resilient decorative articles having embossed elevated and depressed decorative portions. Another object of this invention is to provide a new and improved method for making embossed decorative articles by means of dielectric heating. A further object of this invention is to provide a new and improved method for making resilient decorative articles having embossed elevated and depressed portions defining a sharp and clear design. These and other objects of the invention will be readily apparent from the following specification and drawings, in which:

Figure 1 is a view of the trim assembly positioned within a dielectric heating press prior to the embossing thereof;

Figure 2 is a plan view of the die;

Figure 3 is a sectional view taken on the plane indicated by line 3—3 of Figure 2;

Figure 4 is a view similar to Figure 1 and showing the dielectric heating press in closed position in an intermediate step of the method prior to the heat cycle;

Figure 5 is a view similar to Figure 4 and showing the heating press and the trim assembly during the heat cycle; and

Figure 6 is a view of the finished trim assembly.

Referring now to Figure 1 of the drawings, a dielectric heating press includes a lower electrode 10 and an upper electrode 12, which is supported by suitable operating means for movement toward and away from the lower electrode 10. The heating press is of a known type which is commercially available and, therefore, it is believed that no further description need be given. An alternating current generator 14 is in series with the upper and lower electrodes and is of the type suitable to impress an alternating current of radio frequency across the press electrodes.

A die 16 is secured in a suitable manner to the upper electrode 12. The die may be made of any suitable thermally and electrically conductive material such as steel, copper, brass, bronze, etc. As may be seen in Figure 2 of the drawings, the die 16 is of V shape and includes an outer continuous embossing rib 18 surrounding an outwardly opening die cavity 20 of V-shape and V cross section which is machined out of the material of the die. Although the die is shown of a particular shape for the purposes of description of the subject invention, it will be understood that other dies of other shapes may be used with equal success, since the method of this invention does not depend upon the particular shape of the die used. However, it will be understood that each die includes an outer continuous embossing rib which surrounds a die cavity opening outwardly of the die.

Referring now to Figure 1 of the drawings, one or more buffer sheets 24 of silicone rubber are placed upon the lower electrode 10 of the press. The buffer sheets act as a resilient support for the trim assembly 26 to insure equal pressure of the die on all areas of the trim assembly engaged thereby and also acts to prevent arcing between the die 16 and the lower press electrode 10 when the press is in closed position and an alternating current of radio frequency is being impressed across the upper and lower electrodes of the press. Although silicone rubber is preferred, the sheets 24 may also be of other materials such as Butyl rubber.

The trim assembly 26 which is supported on the buffer

sheets 24 includes an outer sheet 28 of heat fusible or thermoplastic trim material, an intermediate layer 30 of heat fusible sponge rubber, and a backing sheet 32. The backing sheet 32 is preferably a woven cloth of water absorbent material, such as cotton or other natural fibers, synthetic fibers, or other materials.

The intermediate layer 30 of sponge rubber is preferably processed on the backing sheet 32 when the sponge rubber is produced so that the backing sheet and the layer of sponge rubber are secured together. The sponge rubber is a soft cellular heat fusible sponge-like highly resilient material which may be formed of natural rubber, various synthetic materials such as Butyl rubber, vinyl chloride resins, neoprene, isocyanate resins, and mixtures of natural rubber and the above synthetic materials. The sponge rubber has a very high resilient property and quickly recovers its shape and form when any deforming pressure is first applied and then removed therefrom. The sponge rubber is also permeable to gases under high pressure conditions with the rate of permeation being very low. The outer sheet 28 may be of any suitable heat fusible or thermoplastic material such as vinyl chloride, vinylidene chloride, and other similar synthetics formed into sheet form. If desired, the outer surface of the sheet 28 may be tooled or otherwise provided with various finishes such as a finish simulating leather. It is also preferable that the sheet 28 be secured to the intermediate layer 30 of sponge rubber by a suitable adhesive, whether thermoplastic or otherwise, in order that the sheet 28 may be assembled with the sponge rubber and backing sheet for ease of handling prior to positioning of the trim assembly 26 within the dielectric heating press.

After the outer sheet 28 of thermoplastic material has been assembled with the intermediate layer 30 of sponge rubber and the backing sheet 32 of water absorbent material, the sheet 32 is moistened prior to positioning of the trim assembly on the sheets 24 within the dielectric heating press.

Since the method of this invention depends on a very close control of the pressure and temperature within the die cavity 20, as will be hereinafter apparent, the amount of moisture applied to the backing sheet 32 must be carefully controlled. Therefore, it is preferable that from 14 to 18 grams per square foot of water be applied to the backing sheet 32. The water may be applied by any suitable method such as roll coating, and need be applied only to the area of the backing sheet which is positioned below the area of the sponge rubber layer and sheet of thermoplastic material to be subsequently embossed. Since the intermediate layer 30 of sponge rubber is not water absorbent, there is only a very slight and negligible wetting of the outer surface of this layer and for all practical purposes, it may be considered that no moisture is absorbed by this layer.

After the backing sheet 32 has been moistened, the trim assembly 26 is then positioned within the dielectric heating press, as shown in Figure 1, with the backing sheet 32 in engagement with the buffer sheets 24 and the moistened area of the backing sheet in general alignment with the die 16, if only the one area of the backing sheet has been moistened. The upper electrode 12 is then moved downwardly until the die 16 engages the trim assembly as shown in Figure 4 of the drawings. When the die engages the assembly, a continuous portion 40 of the sponge rubber layer 30 which is underneath the embossing rib 18 of the die is compressed and is in the shape of a V. The portion 42 of the sponge rubber layer which is within the embossing rib 18 will be forced slightly upwardly within the die cavity 20 of the die and will also force a portion 44 of the sheet 28 upwardly within the die cavity. The pressure of the embossing rib 18 on the area 40 of the sponge rubber layer and the area 46 of the sheet 28 is between 200 and 600 lbs. per square inch with a pressure of 400 lbs. per square inch preferably

being used. Since the portion 40 of the sponge rubber layer is compressed and held between the embossing rib 18 of the die and the lower electrode 10 of the press, the cellular construction of this portion is destroyed so that there is no permeation of gases possible therethrough despite the existence of high pressure within the portion 42 of the layer and the die cavity 20 as will be explained.

After the press has been closed as shown in Figure 4, an alternating current of radio frequency is impressed across the upper and lower electrodes of the press by the A.C. generator 14 so that an electric field will be generated between the die 16 and the lower electrode 10. The voltage of the field will preferably be in the range from 2,000 to 2,200 volts and the frequency will preferably be in the range from 1 to 100 megacycles with a frequency of 14 megacycles being preferable. As the electric field passes between the die 16 and the lower electrode 10, the water which has been absorbed by the backing 32 of the trim assembly starts to be converted into steam and at 10 the same time the area 46 of the thermoplastic trim material beneath the embossing rib 18 together with the compressed portion 40 of the sponge rubber layer become heated. As the water turns to steam, it will expand as is 15 well known. Since the portion 40 of the sponge rubber 20 is compressed to provide a continuous barrier, the steam cannot escape through this portion of the sponge rubber and, therefore, will force both the portions 44 of the thermoplastic trim material and 42 of the sponge rubber layer 30 upwardly into the die cavity 20 as it expands.

As previously mentioned, the sponge rubber layer 30 is of cellular construction. However, the rate of permeability of the sponge rubber by the steam is such that the steam cannot immediately permeate the sponge rubber to escape into the die cavity 20 and, therefore, the steam will initially force the portion 42 of the sponge rubber layer and the portion 44 of the thermoplastic trim material into the die cavity and compress the portion 42 before there is any substantial permeation of the portion 42 of the sponge rubber layer by the steam. Thus, as the steam is initially formed and expands, it will force the portion 42 of the sponge rubber layer upwardly into the die cavity 20 so that the portion 44 of the thermoplastic trim material will be forced upwardly into substantial conformity with the shape of the die cavity. Since 40 the die 16 is not heated by the electric field passing therebetween and the lower electrode 10, the portion 44 of the thermoplastic trim material will not be heated to its softening temperature by the initial expansion of the steam and therefore will not initially conform to the exact contour of the die cavity, particularly so if the die has sharp corners such as the peak of the V-shaped die cavity 20. The die 16 will also act to quench the portion 44 of the thermoplastic trim material in engagement with the die cavity 20 and the portion 44 of the thermoplastic material in turn will quench the sponge rubber layer immediately adjacent thereto.

Thereafter, as the heating continues, the steam will gradually permeate the portion 42 of the sponge rubber layer and come into contact directly with the portion 60 44 of the sheet 28 of thermoplastic material in engagement with the die cavity 20. This will soften the portion 44 of the thermoplastic material so that the material will exactly conform to any sharp contours of the die cavity under the pressure of the steam acting directly thereagainst and the pressure of the portion 42 of the sponge rubber layer. The permeation of the portion 42 of the sponge rubber layer by the steam will also fuse this portion under compression so that the portion will 65 retain its compressed shape after removal of the trim assembly from the die.

The heating cycle during which the alternating current of radio frequency is impressed across the upper and lower electrodes will preferably be a period of 15 70 seconds. Thereafter, the electric field is turned off but

the die 16 is not moved out of engagement with the trim assembly for a period of another 5 seconds. During this latter 5 seconds, the portion 42 of the thermoplastic trim material in engagement with the die cavity is quenched by the die so as to retain its shape after removal of the trim assembly from the die.

During the formation of the elevated portion of the decorative article, as previously explained, the portion 40 of the sponge rubber layer which is compressed between the embossing rib 18 of the die and the lower press electrode is heated dielectrically, and also somewhat by the entrapped steam, so that this layer will be fused while compressed. The area 46 of the thermoplastic material immediately beneath the embossing rib is also softened dielectrically so as to be fused to the sponge rubber layer.

Thereafter, when the press is opened, the finished trim assembly may be removed. As shown particularly in Figure 6 of the drawings, the trim assembly includes an elevated portion 50 of V shape and also V cross section which conforms exactly to the shape of the die cavity 20 of die 16, with this elevated portion being bounded by a continuous depressed portion 52 of the shape of the embossing rib 18 of the die 16. The elevated portion 50 is comprised of an outer covering of thermoplastic trim material conforming exactly to the contour of die cavity 20 and a backing layer of fused and compressed sponge rubber, with the degree of compression being greatest immediately adjacent the depressed portion 52 and least adjacent the apex of the V cross section. The depressed portion 52 is also comprised of an outer covering of thermoplastic trim material and a backing layer of fused and substantially totally compressed sponge rubber.

As previously mentioned, the method of this invention depends on a very close control of the pressure and temperature within the die cavity 20, and therefore the amount of moisture applied to the backing sheet must be carefully controlled. If insufficient moisture is applied to the backing sheet, then the volume of steam may not be sufficient to compress the portion 42 of the sponge rubber layer 30 within the die cavity to force the portion 44 of the sheet 28 of thermoplastic material to conform to the contour of the die cavity. Also, the reduced volume of steam will not permeate the sponge rubber layer to any extent so as to fuse this layer while under compression and will also not soften the portion 44 of the sheet of thermoplastic material. Thus, the assembly will not retain its shape after removal from the press.

Likewise, if there is an excess volume of steam caused by the application of excess water to the backing sheet 32, then the portion 42 of the layer of sponge rubber may become so compressed by the initial expansion of the steam to prevent any permeation and fusion thereof by the steam, except perhaps for the immediate surface layer adjacent the backing sheet 32. This will also prevent the steam from softening the portion 44 of the sheet of thermoplastic material to cause this portion to conform exactly to the shape of the die cavity 20.

The amount of water applied to the backing sheet 32 also controls the temperature of the sponge rubber layer during the compression and fusion thereof. This temperature must be kept below the degradation temperature of the sponge rubber or otherwise the sponge rubber will become charred or destroyed. In the particular assembly shown herein, the temperature of the sponge rubber is approximately 300° F. during the compression and fusion steps of the method. It will also be noted that the portion 44 of the thermoplastic trim material will also be destroyed if the temperature of the adjacent portion of the portion 42 of the sponge rubber layer becomes heated to an extremely high temperature.

Although preferred heating cycle quench cycle times have been hereinbefore mentioned, these times are necessarily dependent on each particular trim assembly, par-

ticularly so depending on the depth of the sponge rubber layer 30. In the arrangement shown, this layer is approximately $\frac{5}{16}$ " thick, and the times hereinbefore specified may be used with success on a sponge rubber layer of this thickness.

Thus, this invention provides an improved method for making decorative articles having embossed elevated and depressed areas so that the finished article includes an integral and well-defined decoration.

What is claimed is:

1. A method of making an article having an elevated decorative portion formed thereon comprising, coating one surface of a gas and vapor pervious cellular heat fusible resilient material with about 14 to 18 grams per square foot of a liquid which is convertible into vapor upon the application of heat and which is chemically inert with respect to said resilient material, causing the opposite surface of said material to be engaged with a die structure having a die cavity opening in face-to-face relation with the said portion of the article to be decorated, relatively moving said die to compress said material sufficiently to destroy the cellular structure of said material about the periphery of said decorative portion so as to leave a pocket of said cellular material within said compressed periphery, dielectrically heating said material sufficiently to convert said liquid to vapor, said vapor initially acting upon the liquid coated surface of said material to urge the material in said pocket upwardly into intimate engagement with the die cavity, continued dielectrically heating of said material causing said vapor to permeate and heat the cellular material within said pocket whereby the compressed portion of said material will be fused and the material in said pocket caused to retain the shape of the die cavity.
2. A method for making an article having an elevated decorative portion integral therewith comprising, coating one surface of a portion of a gas and vapor pervious cellular heat fusible resilient material with about 14 to 18 grams per square foot of a liquid which is convertible into vapor upon the application of heat and which is chemically inert with respect to said resilient material, confining the portion of the article to be formed into the elevated portion by compressing said material within a substantially closed die structure having a die cavity of the decorative portion opening to the opposite surface of said material, and thereafter dielectrically heating the liquid within the die structure to convert the liquid to heated vapor, the confined vapor initially acting on the liquid coated surface to urge the confined material into intimate engagement with the die cavity, continued dielectric heating of said material causing said vapor to permeate and heat the confined cellular material whereby the cellular material adjacent said die will be fused upon itself to retain the shape of the die cavity.
3. A method for making a resilient laminated article having elevated decorative portions integral therewith comprising, assembling a sheet of thermoplastic material with a backing of a gas and vapor pervious cellular heat fusible resilient material, coating the surface of the cellular material opposite said sheet material with a liquid which is convertible into vapor upon the application of heat and which is chemically inert with respect to said sheet and said resilient material, compressing a continuous boundary area of a portion of the laminate within a die having a die cavity of the desired decorative configuration opening to the thermoplastic sheet material, and thereafter dielectrically heating the liquid within the die to convert the liquid to vapor whereby the confined vapor pressure will initially act against the liquid coated surface of the cellular material compressing this material so as to force the thermoplastic material within the die cavity, continued dielectric heating of the materials causing said vapor to permeate and heat the cellular material whereby the compressed portion of the latter material will fuse upon itself and the sheet material will fuse to

the subadjacent cellular material causing the laminate to retain the shape of the die cavity, the amount of said liquid coated on the surface of the cellular material being such as to produce sufficient vapor pressure to force the thermoplastic material into conformity with the die cavity while leaving the cellular material gas and vapor pervious.

4. A method of making an article as set forth in claim 3 in which the liquid is applied to the surface of said cellular material in the amount of between 14 to 18 grams per square foot of said surface, and further in which said material is compressed between 200 and 600 pounds per square inch.

5. A method of making an article as set forth in claim 3 in which the liquid is applied to the surface of said cellular material in the amount of between 14 to 18 grams per square foot of said surface, and in which the

temperature of said material is approximately 300° F. during the compression and fusion steps.
